UNITED STATES PATENT OFFICE.

PAUL WOLF, OF ZWICKAU, GERMANY.

MINER'S AND LIKE ELECTRIC SAFETY-LAMP.

1,100,226.

Specification of Letters Patent. Patented June 16, 1914.

Application filed January 30, 1913. Serial No. 745,206.

To all whom it may concern:

Be it known that I, PAUL WOLF, a subject of the German Emperor, residing at Zwickau, Saxony, in Germany, have invented certain new and useful Improvements in Miners' and like Electric Safety-Lamps, of which the following is a specification.

The object of this invention is to provide improved means for fastening electric lamp bulbs in miners' and like lamps, such fastening enabling the bulb to be fixed and removed in a convenient manner without removing the glass cylinder of the lamp.

The invention is illustrated in the accompanying drawing, in which,

Figure 1 is a central vertical section of the upper part of the lamp according to one construction. Fig. 2 is a similar section of the lamp according to another construction, 20 and Fig. 3 is a bottom plan view of the bulb-holder shown in Fig. 2. Fig. 4 is a sectional view illustrating a third form of construction.

Referring in the first instance to Fig. 1, a designates the lamp bulb, which has a foot b provided with a metal sleeve c. An insulating plate d carries the glass cylinder e of the lamp and has a central aperture provided with a metal lining f. The latter is in contact with a metal plate g let into the plate d. The lamp is inserted from below into the socket formed by the said aperture and its metal lining, the upward movement of the bulb being limited by a flange h at the bottom of the sleeve c, and a washer or packing ring i being inserted between such flange h and the plate d to make a tight joint.

The lamp is held up in its socket by means of a spring k, which is pivoted to the underside of the plate d so that it can be turned aside for inserting the electric lamp bulb. The spring k is provided with a depression for engagement with a projecting plug m to which one of the leading-in wires z is connected. The spring k does not make contact with the sleeve c, but is in contact with the terminal n² of the battery n when the plate is in position in the lamp as shown in Fig. 1. The other leading-in wire z is joined to the sleeve c, and is accordingly electrically connected by the socket lining f to the plate g, which rests on the terminal n² of the battery.

In the construction shown in Figs. 2 and 3, 55 the lamp bulb a¹ is also inserted from below through an aperture in an insulating

plate d¹ carrying the glass cylinder e¹ of the lamp and has a foot b¹ fitting in said aperture, but in this case the leading-in wires z¹ are joined at the foot of the bulb, to contact plates o and p respectively, which are fixed to the foot and project somewhat beyond the circumference thereof. These plates o and p form stops limiting the upward movement of the bulb, and when the bulb has been inserted it is rotated so that the plates o and p are engaged with metal hooks q and r respectively, joined to contact plates s and t fixed to the under-side of the insulating plate d¹. When the insulating plate d¹ is in position, as shown in Fig. 2, the plates s and t rest on the terminals n² and n³ respectively of the battery n¹.

The construction shown in Fig. 4 is in its general arrangement similar to that shown in Fig. 1, but the sleeve c² around the foot of the lamp is screwed into the lining or socket f² in the aperture of the insulating plate d².

What I claim as my invention and desire to secure by Letters Patent of the United States is:—

1. In an electric safety lamp, the combination of a frame, a lamp bulb having a base portion, an element having a transparent portion and completely surrounding the said bulb and carried by said frame, an insulating base for said frame closing the bottom thereof, said insulating base having an opening making a close fit with said base portion of the lamp bulb, a contact on the periphery of said base portion of the lamp bulb and connected to the lighting element of the lamp, a second contact on said insulating base of the frame coöperating with said first contact and a third contact on said base portion of the lamp bulb and connected to the lighting element carried by said insulating base serving to hold said base portion of the lamp in position within said opening and coöperating with said third contact.

2. In an electric safety lamp, the combination of a frame, a lamp bulb having a base portion, an element having a transparent portion and completely surrounding said bulb, said element being carried by said frame, an insulating base for said frame completely closing the bottom thereof, said insulating base having an opening whereby to make a close fit with said base portion of the lamp bulb, a contact on the periphery of said base portion of the lamp bulb and con-

2
nected to the lighting element of the lamp, a second contact on said insulating base of the frame coöperating with said first contact, a third contact on said base portion of 5 the lamp bulb and connected to the lighting element of the lamp, and a flexible conducting element carried by said insulating base serving to retain said base portion of the lamp in proper position within said opening and coöperating with said third contact.

3. In an electric safety lamp, the combination of a frame, a lamp bulb having a base portion, the maximum cross section of which is at least as large as the maximum 15 cross section of the bulb proper, an element having a transparent portion and completely surrounding said lamp bulb, said element being entirely carried by said frame, an insulating base for said frame closing the bottom thereof, said insulating base having an 20 opening making a close fit with said base

portion of the lamp bulb, whereby said lamp bulb may be passed through said opening for positioning the lamp bulb, a contact on the periphery of said base portion of the lamp 25 bulb and connected to the lighting element of the lamp, a second contact on said insulating base of the frame coöperating with said first contact, a third contact on said base portion of the lamp bulb connected to 30 the lighting element of the lamp bulb, and a conducting element carried by said insulating base serving to hold said base portion of the lamp bulb in position within said opening and coöperating with said third 35 contact.

In witness whereof I have signed this specification in the presence of two witnesses.

PAUL WOLF.
